ARTICLE CONTAINER AND STAND

William Ehrlich, Chicago, Ill., assignor of forty-five per cent to Albert J. Flie, Chicago, Ill.

Application June 28, 1933, Serial No. 677,989

5 Claims. (Cl. 206—44)

This invention relates to an improved article container and stand, and has for one of its principal objects the provision of means whereby an article of a certain size or shape may be 5 suitably contained in a support or display stand for transportation, display and merchandising purposes.

One of the important objects of this invention is to provide an article container and stand 10 which shall be particularly adapted for use with pies, cakes or the like, whereby the same will be preserved in a satisfactory manner for proper delivery to the ultimate consumer while at the same time, the article is continually kept in an 15 attractive and palatable state.

Another object of the invention is the provision of a display stand and container for pies, cakes or the like which shall be economical to manufacture, simple of construction, easy of application, and which will positively support the pie or other article during handling, and which moreover shall be capable of ready and instant removal whenever desired.

Still another and further important object of 25 the invention resides in the provision of a display stand and container support for pies which shall provide for a free circulation of air and consequent ventilation of the hot pies when placed therein, so that sogginess and any other 30 consequent damage to the product is avoided.

Other and further important objects of the invention will be apparent from the disclosures in the accompanying drawing and following specification.

35 The invention, in a preferred form, is illustrated in the drawing and hereinafter more fully described.

In the drawing:

Figure 1 is a plan view of a strip of cardboard, 40 metal or the like from which the improved article container and support of this invention is adapted to be made.

Figure 2 is a sectional view of the strip shown in Figure 1.

45 Figure 3 is a sectional view of the device, showing the same in position around a pie or similar article of merchandise.

Figure 4 illustrates a modification of the invention.

50 Figure 5 shows one end of a strip from which the modification of Figure 4 is constructed.

Figure 6 is a top plan view of a pie plate or similar container used in conjunction with the strip of Figure 5 which is formed into a band to 55 produce the container shown in Figure 4.

Figure 7 is a top plan view of the device of Figure 4, showing a detail of the invention.

Figure 8 illustrates another modification of the invention.

Figure 9 is an end view of the strip shown in 5 Figure 8.

Figure 10 is an assembled top plan view of the modification illustrated in Figure 8.

Figure 11 is a partial front elevation of a further modification of the invention. 10

Figure 12 is a sectional view of the embodiment illustrated in Figure 11.

As shown in the drawing:

The reference numeral 10 indicates generally a strip of cardboard, thin metal, Celluloid, or 15 other material from which the combined article container and display stand of this invention is constructed.

As best shown in Figure 2, the strip 10 has its upper and lower edges 12 and 14 bent downwardly and upwardly respectively so as to form a doubled and accordingly stronger edge. Inwardly struck tabs or the like 16 and 18 are formed integral with the strip 10, these being preferably of the shape shown in Figure 1, but 25 which obviously can be of some other shape or design as desired or convenient.

From the illustration of Figure 3, it will be evident that these tabs 16 and 18 are adapted to receive and support the peripheral outer 30 edges of the pie plate or similar container, about the circumference of which the strip 10 is placed after having been originally formed into a circular band of an inside diameter substantially equal to the outside diameter of the pie plate 20 with 35 which it is adapted to cooperate.

The pie or other material 22 in the plate is preliminarily covered with a sheet of material, preferably tough and transparent, as one of the well-known cellulose compositions now on the 40 market, and the area of this material 24 is of sufficient extent so that its edges overlap the edges of the pie plate 20 to a sufficient extent so that when the band 10 is pushed downwardly over the pie plate, the inner ends of the tabs 45 16 and 18 will securely grip the periphery of the plate 20 and also the juxtaposed edges of the transparent cover 24, whereby a unitary article results.

The material of the strip 10 is sufficiently resilient so that the tabs 18 will spring back into position as shown in Figures 2 and 3 after having been pushed over the periphery of the pie plate 20, thereby securely holding both the pie and the plate in the band which then acts as 55

a display container. The gripping action of the inner ends of the tabs 16 and 18 upon the sheet of transparent material 24 as doubled over about the edges of the pie plate 20 will securely retain 5 all parts of the device in desired assembled relationship and positively prevent the pie 22 from falling out of the plate even though the container be accidentally dropped or even turned upside down. A certain amount of strength is inherent 10 in the material of the container whether of cardboard, metal or other material whereby the edges of the pie or other product, and in fact, the entire product will be securely protected against undesirable blows, shocks or other damaging 15 actions.

In Figures 4 to 7 inclusive is shown a modified form of the invention wherein a pie plate 26 has its outer edge or periphery formed with a series of integral projections or the like 28 which 20 may be of any desired number, preferably from four to ten. These projections are adapted to be fitted into corresponding slots 30 formed in a strip of paper, cardboard, metal, Celluloid or the like 32.

25 The pie 34 in the plate 26 is likewise covered with a transparent sheet of some cellulose material or the like 36, and the edges of this sheet extending around the edges of the projections 28 will be securely clamped between these projections and the edges of the corresponding slots 30 as best shown in Figure 4 when the device is assembled. This assembly, as in the case of the other modifications, simply consists of pushing the band 32, which is formed into a circular 35 or other corresponding shape, down over the edges of the pie plate or similar container, whereby the projections 28 will be slightly displaced or bent downwardly until such time as they come into alignment with the slots 30, 40 whereupon the natural resiliency of the material will cause the projections to again spring outwardly, retaining the assembly in the proper desired relationship.

In order that the band be placed in proper 45 interfitting relationship with the projections, a marking device is provided in the form of a semi-circular indentation or the like 40 formed in one of the projections which then produces two small projections 42 adjacent the indentation 48, and this is used for aligning the overlap 44 of the joined strip therewith so that an accurate interfitting of all the parts will positively result when the assembly is started as above indicated.

55 A still further modification of the invention is illustrated in Figures 8, 9, and 10 wherein a band 46 is formed of some corrugated material such as paper, cardboard, metal or the like, and into which slots 48 are cut at certain portions 60 of the inwardly extending corrugations as best shown in Figure 9, whereby a space is provided for the reception and retention of the edge of a pie plate 50 or the like, together with an associated pie covering such as the transparent 65 wrapper 24 or 36.

In the modification shown in Figures 1, 2, and 3, the inwardly struck tabs 18 provided ventilating openings for the escape of steam and other hot gases which might be in the pie when it is 70 first baked, and similar openings may be provided in the strips 32 and 46 whereby sogginess of the contained product is prevented.

It will be evident that herein is provided a novel and attractive display device and container for various articles of merchandise, par-

ticularly food products such as pies and cakes, and which may be made economically and simply and out of almost any material. Furthermore, proper ventilation of hot pies or other products is provided for, quick removal of the device is rendered possible, and an attractive and satisfactory package results. The inherent resiliency of the parts themselves allows of ready assembly while at the same time providing a package which is not likely to come apart even under 10 severe conditions of usage or handling. The corrugated support shown in Figures 8, 9 and 10 may be surrounded with an ornamental band or the like which, in that event, should be slightly over-size so as to allow of expansion of the corrugated strip, and this outer band may be accordingly fastened by glue or the like to several points of the corrugated element so as to allow for such expansion, while at the same time retaining the parts in proper relationship.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. An article container and display support, comprising a band, a supporting platform adapted to be associated with the band, said supporting platform provided with integral projections for insertion in corresponding slots in the band, and means for aligning the projections and slots in assembly, said means comprising a pair of relatively small adjacent projections separated by a distinctive notch.

2. An article container and display support, comprising a band, a supporting platform adapted to be associated with the band, said supporting platform provided with integral projections for insertion in corresponding slots in the band, and means for aligning the projections and slots in assembly, said means comprising a pair of relatively small adjacent projections separated by a distinctive notch, said notch adapted to be interfitted with the overlapped portion of the band.

3. A commodity wrapper comprising a plate member for supporting the commodity and having a peripheral vertically yieldable flange; a flexible cover sheet disposed over said commodity and having its marginal portions depending over the flange of said plate; a preformed flexible endless band member having its ends permanently secured together surrounding said plate and the marginal portions of said cover sheet; said band member having a yielding spring engagement with said plate flange, and a plurality of spaced elongated apertures in said band member receiving adjacent portions of said plate flange and cover sheet, whereby vertical movement of said permanently endless band member relative to said plate draws said cover sheet substantially taut over the commodity, engages portions of said flange within said apertures and thereafter maintains the wrapper in assembled position by the spring engagement of said flange portions with said spaced apertures to clamp adjacent marginal portions of said cover sheet therebetween.

4. A commodity wrapper comprising a plate for supporting the commodity and having a peripheral vertically yieldable flange, a flexible cover sheet disposed over said commodity and

- having its marginal portions depending over the flange of said plate, a preformed flexible endless band member surrounding said plate and the marginal portions of said cover sheet and having a yielding spring engagement with the plate flange, said band having an internal diameter less than the external diameter of said plate flange, and a plurality of spaced elongated apertures in said band member for receiving adjacent portions of said plate flange and cover sheet, whereby vertical movement of said band member relative to said plate draws said cover sheet substantially taut over the commodity and thereafter maintains the wrapper in assembled position by the spring engagement of said flange portions with said spaced apertures to clamp adjacent marginal portions of said cover sheet therebetween. 5
10. A commodity wrapper comprising a plate member for supporting the commodity and having a peripheral flange provided with spaced vertically flexible projecting portions, a flexible cover sheet disposed over said commodity and having its marginal portions depending over the flange of said plate, a preformed flexible endless band member surrounding said plate and the 5 marginal portions of said cover sheet, said band member having its ends permanently secured together and having a yielding spring engagement with the plate flange, and a plurality of spaced elongated apertures in said band member 10 for receiving the outwardly projecting portions of said plate flange and adjacent portions of said cover sheet, whereby vertical movement of said band member relative to said plate draws said cover sheet substantially taut over the commodity and thereafter maintains the wrapper in assembled position by the spring engagement of said outwardly projecting flange portions with said spaced apertures to clamp adjacent marginal portions of said cover sheet therebetween. 15
20. WILLIAM EHRLICH.
